UNITED STATES PATENT OFFICE.

IRV J. YOUNG, OF ST. LOUIS, MISSOURI.

WOVEN-WIRE FABRIC.

No. 884,833.

Specification of Letters Patent.

Patented April 14, 1908.

Application filed February 5, 1897. Serial No. 355,962.

To all whom it may concern:

Be it known that I, IRV J. YOUNG, a citizen of the United States, and resident of St. Louis, Missouri, have invented certain new and useful Improvements in Woven-Wire Fabric, of which the following is a specification containing a full, clear, and exact description, reference being had to the accompanying drawings, forming a part hereof.

10 My invention relates to a woven wire fabric, which is particularly adapted for floor mats, although it may be advantageously used in the manufacture of wire mattresses for beds, for seat backs, hammocks, as metal lathing, or for any purpose where a light, strong, and durable wire fabric is essential.

The objects of my invention are: first, to construct a wire fabric of any length and width, by weaving or forming said fabric 20 from a single wire by suitable machinery; second, to so form the loops in the wire that the finished fabric will lie perfectly flat without buckling or curling up in any direction; third, to form a simple edge or finish on the 25 sides of the fabric.

To the above purposes, my invention consists of the features of novelty hereinafter described, claimed, and shown in the accompanying drawings, in which:

30 Figure 1 is a plan view of one corner of a floor mat formed of my improved fabric; Fig. 2 is an elevation or edge view of the mat seen in Fig. 1; Fig. 3 is a detail section taken on the line 3—3 of Fig. 1; Fig. 4 is a perspective view of a strand of wire, illustrating the shape of the loops and the legs which are formed between said loops.

My improved fabric is constructed of a single strand of wire, by means of automatic 40 machinery, and said strand of wire is carried alternately across the machine, and by the needles, or loop forming members thereof, is formed into a series of angular horizontally disposed loops, each comprising a short 45 transversely disposed portion 1, and the longitudinally disposed portions 2, which loops are arranged at equal distances apart; and connecting the adjacent pairs of the portions 2 are the curved legs 3, which are bent 50 downwardly and laterally so that the extreme lower ends of said legs occupy positions approximately one-half way between the ends of the horizontally disposed loops.

The portions 2 of each loop are drawn together slightly at the end opposite the portion 1, in order that they will readily pass through and fit in the corners formed between the portions 1 and 2 of the next adjacent loops.

The legs 3 are bent abruptly down and forward from the ends of the portions 2, as designated by 4, in order to fit snugly around the ends of the portions 1, and all of the legs 3 are bent or curved laterally in order to form a yielding or resilient support for the horizontal 55 portion of the mat formed by the horizontally disposed loops, and also to cause the mat to lie perfectly flat when upon the floor, or positioned against any flat surface.

The edges of the fabric are finished by extending the outside portion 2 of each alternate horizontal loop for a distance beyond the portion 1, and forming a horizontal loop 5 immediately adjacent the outside row of horizontal loops; and the forward ends of the 55 outer portion of each loop 5 being looped around the rear end of the adjacent loop 5, as designated by 6, and from thence the wire is bent downwardly and laterally to form the legs 7, which are in transverse alignment 60 with the legs 3; and from said legs 7 the wire is fed across the fabric to form the alternate horizontal loops comprising the portions 1 and 2 and the legs 3.

When floor mats are constructed of wire 65 fabric of my improved construction, the ends thereof are finished by being provided with metallic plates, or bars, as shown in Figs. 1, 2, and 3.

A wire fabric of my improved construction 70 is simple, inexpensive, can be very cheaply manufactured, is composed of a single strand of wire, and is provided with resilient legs 75 which yieldingly support the upper portion of the fabric, and cause the same to lie perfectly flat without buckling in any direction.

I claim:

A wire fabric, woven from a single strand of wire, which wire is formed into a series of rows of angular horizontally disposed loops, 100 the ends of the loops of one row being looped through the ends of the next adjacent row, and the portions of the wire between all of the loops being bent to form resilient legs 105 which are curved downwardly and laterally, and all of said legs being bent in the same

direction, and the edges of the fabric being finished by the formation of a series of horizontal loops occupying the same plane with the horizontally disposed angular loops, and 5 the end of each edge horizontal loop being bent or looped around the end of the next adjacent edge horizontal loop.

In testimony whereof, I have signed my name to this specification, in presence of two subscribing witnesses.

IRA J. YOUNG.
